MACHINE AND METHOD FOR MAKING
SOLID COMMINUTED MATERIAL

Joseph L. Stecher, Wilmington, Del., Marion G. Amick, Boothwyn, Pa., and Charles E. Daniels, Wilmington, Del., assignors to E. I. du Pont de Nemours & Company, Wilmington, Del., a corporation of Delaware

Application November 17, 1933, Serial No. 698,384

6 Claims. (Cl. 29—4.5)

This invention relates to a machine and method for making solid comminuted material directly from molten material and to the product obtained thereby.

5 In the manufacture of alkyl lead compounds, an alkyl halide is reacted with a lead-sodium alloy. In order for this reaction to take place in an efficient and economical manner, the lead-sodium alloy must be finely divided and in such 10 condition that it will react readily with the alkyl halide. In the preparation of such alloy, it has generally been considered necessary to melt the sodium and lead together and cast the material in the form of billets or "pigs". When the cast 15 material has cooled and solidified, it has then become necessary to break them up into pieces of a size to be readily handled and then ground or crushed in a crusher or other form of grinding mill. This method of making the finely divided 20 lead-sodium alloy has proved to be very unsatisfactory, inefficient, and wasteful. This type of alloy is subject to rapid deterioration in the atmosphere, particularly when hot. Such deterioration results in a waste of valuable material 25 as the deterioration products will not take part in the reaction to form the desired reaction products. Also, when it is attempted to grind this material, the material tends to pack and jam, requiring stopping of the grinding operations, dismantling of the crusher or grinding mill 30 and cleaning of the same. This results in a waste of much time and labor and the loss of valuable material due to oxidation and the action of moisture in the atmosphere necessarily admitted into contact with the alloy in the mill when the mill is dismantled.

Other metals and their alloys have similar characteristics and properties which render it extremely difficult and costly to prepare them in finely divided form.

An object of the present invention is to provide a novel device which is adapted for the preparation of solid comminuted material directly from molten material. A further object is to provide such a device whereby such solid comminuted material may be made in a more efficient, economical and rapid manner than has been possible with devices heretofore employed. A still further object is to provide a novel method of manufacturing solid comminuted material directly from molten material. Another object is to provide a new method whereby solid comminuted material may be manufactured in a more efficient, economical and rapid manner. Still another object is to produce comminuted material

in a novel form. Other objects are to advance the art. Still other objects will appear hereinafter.

These objects may be accomplished in accordance with our invention which comprises the novel device disclosed in the drawings and described hereinafter, together with the method of employing the same and the products produced thereby.

Reference is to be had to the accompanying drawings forming a part of this specification, in which similar reference characters refer to similar parts throughout the several views.

Figure 1 is an elevational view of our device with parts of the bed plate broken away for the sake of clearness in illustration.

Figure 2 is a vertical longitudinal section of the apparatus shown in Figure 1.

Figure 3 is an enlarged elevational view in perspective of the rotary member with the surrounding shell shown partly in section to illustrate the relation of parts.

Figure 4 is a perspective elevational view of one of the edged tools detached from the rotary member.

Figure 5 is a perspective view of the stationary shell with parts broken away and the end flanges removed to more clearly illustrate the arrangement of the partitions.

Figure 6 is a view in cross section of the shell, taken on lines 6—6 of Figure 2.

Briefly, our device comprises essentially a stationary jacketed shell having an inner smooth cylindrical surface and a rotary member positioned within the shell and having an outer cylindrical surface positioned adjacent to but spaced from the inner surface of the shell. The rotary member has a plurality of edged tools rigidly secured to and projecting from the outer cylindrical surface thereof, and having their edges positioned closely adjacent to the inner cylindrical surface of the shell. We term these tools "teeth", and it appears to us that they have a cutting action. These tools on the rotary member are sufficient in number and so positioned relatively to each other that they form an interrupted spiral advancing from the charging end to the discharging end of the shell and sweeping the entire inner cylindrical surface of the shell in a single rotation of the rotary member. These projections are adapted to throw molten material, deposited on the rotary member, onto the inner cooled cylindrical surface of the shell, where the molten material is cooled and solidified, remove the solidified material from the in-

25

35

55

inner cylindrical surface of the shell, comminute such removed material, and move it to the discharge outlet of the shell. It appears to us that the material is cut and ground.

- 5 The stationary shell comprises an upper semi-cylindrical half 10 and a lower semi-cylindrical half 12. Each of the halves has an outwardly projecting flange 14 extending along each of the longitudinal edges thereof provided with openings for bolts 16 or other suitable securing devices for properly securing the two halves together. Each semi-cylindrical half, also, has an outwardly projecting annular flange 18 at each end thereof. The upper cylindrical half of the shell has a charging inlet 20 positioned at the top and at one end thereof. The lower cylindrical half has a large discharge outlet 22, substantially rectangular in horizontal cross section, positioned at the bottom thereof. This discharge outlet is at the opposite end of the shell from the charging inlet.

Each semi-cylindrical half also has an outer substantially semi-cylindrical shell or jacket 24 covering the outer surface thereof but spaced therefrom so as to provide a semi-annular space 26. This space 26 is provided for the circulation of a fluid heat transfer medium for maintaining the shell and the inner cylindrical surfaces thereof at a predetermined temperature. The jacket on the upper half of the shell has two inlets 28 positioned at opposite sides of the jacket adjacent to the longitudinal flanges thereof at one end. An outlet 30 is provided at the top of the jacket near the opposite end thereof. The jacket, on the lower half of the cylindrical shell, has a fluid inlet 32 positioned at the bottom and adjacent one end thereof. Two fluid discharge outlets 34 are provided at opposite sides of the jacket of the lower cylindrical half and adjacent longitudinal flanges 14 at the other end thereof.

Short partitions 36 are positioned in the spaces 26 between the jackets 24 and the semi-cylindrical shell halves 10 and 12. These partitions 36 are provided in longitudinally spaced pairs, the members of each pair extending circumferentially from the longitudinal flanges 14 toward each other. However, these partitions terminate short of the median of the semi-cylindrical halves and of each other so that there is an opening between their opposed ends for the passage of fluid around the same. Longer partitions 38, positioned in the space 26, extend circumferentially across the medians of the semi-cylindrical halves and have their ends terminating short of the longitudinal flanges 14 and intermediate of the lengths of partitions 36. These partitions 38 are positioned intermediate the pairs of partitions 36 longitudinally of the semi-cylindrical halves. Additional short partitions 40 are provided in the space 26 of the lower cylindrical half of the shell adjacent the inlet 32. These short partitions 40 are spaced from the flanges 14 and the median of the cylindrical half. These additional partitions 40 prevent the accumulation of steam or other vapors of the heat transfer medium adjacent the flanges 14 at the inlet end of the jacket.

The lower half of the shell is provided with brackets or feet 42 for supporting the shell on a suitable bed plate 44. These feet 42 are four in number, there being two on each side of the shell. These feet may be secured to the bed plate by bolts or other suitable securing means.

The ends of the shell are hermetically closed by circular headers 46 which are secured to the

annular flanges 18 by means of bolts or other suitable securing means. The headers are provided with circular openings at the center thereof for the rotating member 50. Suitable packing boxes are provided for preventing gases or liquids from entering or leaving the shell through the openings during operation.

The rotary member comprises a shaft 48 and a drum supported by and rigidly secured thereto. The drum comprises a cylinder 50 closed at the ends by circular walls 52. The circular walls 52 have outwardly projecting cylindrical members 53 which are adapted to project and rotate in the circular openings and packing boxes in the headers 46. The drum 50 is provided with an inner cylindrical shell or jacket 54 adjacent to but spaced from the cylinder 50 to provide an annular space 56 for the circulation of a heat transfer medium. A partition 58 is positioned in the space 56 and surrounds the jacket 54. This partition 58 is in the form of a spiral advancing from one end to the other of the annular space 56.

One end of the shaft 48 is bored to form a fluid inlet 60 which extends into the drum and connects with inlet 62 opening into the space 56 through the jacket 54 adjacent one end thereof. The other end of the shaft 48 is provided with a fluid outlet 64 which extends into the drum and connects with a fluid outlet 66 opening into the space 56 at the opposite end of the jacket to the inlet 62 and at the opposite side of the jacket 54. The ends of the shaft 48 are provided with suitable stuffing boxes 68 and nipples 70 for connection to a supply of the fluid heat transfer medium to be circulated through the annular space 56.

The cylinder 50 has an outer cylindrical surface concentric with the inner cylindrical surface of the shell. Also, the cylinder 50 is of such diameter that the outer cylindrical surface thereof is positioned adjacent to the inner cylindrical surface of the shell but spaced therefrom. The cylinder 50, in the outer surface thereof, is provided with openings or sockets for elements 72. These elements are rigidly secured to the cylinder 50 and project outwardly from the cylindrical surface thereof in a radial direction. The edges of the elements are positioned closely adjacent to the inner cylindrical surface of the shell so as to remove and scrape therefrom, material which may be deposited on such inner cylindrical surface. These elements are arranged in horizontal rows extending longitudinally of the drum, each row containing a plurality of such elements. The elements in the various rows are so positioned, relatively to the elements in the other rows, that they form one or more complete broken spirals advancing from the charging end of the shell toward the discharge opening thereof and will sweep substantially the entire inner cylindrical surface of the shell so as to remove material deposited upon any portion of such inner cylindrical surface. These elements are made of tool steel and are ground and shaped in the manner of a metal finishing tool having a front clearance of about 5° and a top rake of about 5°. These proportions of the elements may be varied a few degrees one way or another to suit the class of material being treated, as is the case of all metal cutting tools. Each element will also have its operating edge set at about 45° to the line of forward travel or rotation of the drum. However, this angle may also be varied in accordance with the material being treated. If desired, these elements may be adjustably secured within 75

their sockets so that the angle of the edges relative to the forward line of travel of the elements may be adjusted for the treating of different materials.

5 The shaft 48 is supported in heavy bearings 74 so that the drum and the elements will run concentrically with the inner cylindrical surface of the shell. These bearings may be supported on the base plate supporting the stationary shell, if desired. The shaft 48 also carries a pulley 76 which is to be connected to a motor or other suitable driving means for rotating the shaft. Also, other means may be employed for rotating the shaft, if desired.

15 By the use of the hereinbefore described device, we are enabled to produce solid comminuted material directly from molten material more efficiently, economically and rapidly than has heretofore been possible. In the operation of this 20 device in accordance with our novel method, the material to be comminuted is charged through the inlet 20 in the molten state. This molten material falls upon the surface of the drum 50 which is rotating at a speed of about 150 to 350 25 R. P. M. The molten material is thrown off from the drum by centrifugal force and against the inner cylindrical surface of the shell. The elements 72 act as paddles, during such rotation, to aid in throwing the molten material against 30 the surface of the shell. The molten material is partly cooled upon coming into contact with the cooled surfaces of the rotary member or drum 50 and further cooled to below its solidifying point upon the inner cylindrical surface of the 35 shell. The molten material thus solidifies upon the inner surface of the shell and the elements thereupon remove the solidified material from the surface of the shell. These elements also act to comminute the material which has been removed. 40 Furthermore, due to the elements being so positioned as to form a broken spiral or helix, the removed and comminuted material is fed by means of the elements toward the discharge outlet where the comminuted material discharges 45 into a suitable container which is preferably in the form of a weighing tank. The rate of feed of the molten material into the device will be varied with the speed of rotation of the rotary member. The size of the comminuted particles 50 produced may also be varied by varying the rate of feed of material for any given speed of the rotary member. For example, if it is desired to make very finely comminuted material, the rate of feed should be slow and the speed of the 55 rotary member should be high. If it is desired to have the comminuted material in larger particles, a greater rate of feed of material should be employed or the speed of the rotary member should be decreased. However, the speed of the 60 rotary member should always be sufficient so that the molten material will be thrown out and away therefrom by centrifugal force. Such speed of the rotary member will, of course, vary with the character of the material being treated.

65 In order to more clearly illustrate the method of operating my device the following example is given:

Example

70 A lead-sodium alloy, comprising 90% lead and 10% sodium in molten state and having a temperature of from 370° to 420° C., was charged into the device at rates of feed varying from 1 to 500 pounds per minute. The rotary member 75 was driven at a speed of from 150 to 350 R. P. M.

The medium circulating through the jackets was a light grade of fuel oil which entered the jackets at about 30° C. and left the jackets at temperatures as high as 150° C. Satisfactory results were obtained at the various conditions within these ranges. When the rate of feed was 100 pounds per minute and the speed of the rotary member was 250 R. P. M., the comminuted material had a particle size of about 60 mesh. When the rate of feed was 200 pounds per minute and the speed of the rotary member was 150 R. P. M. the particle size of the comminuted material was about 40 mesh.

We have further found that the material, produced in accordance with our method employing our novel device, has certain characteristics and properties which comminuted materials, obtained by other methods, do not have. The material, produced in accordance with our method, will usually be found to be in the form of small 20 agglomerates which are porous. These characteristics of the material, produced in accordance with our process, are of material advantage where the comminuted material is to be employed in a 25 chemical reaction. Where the comminuted material either acts as a catalyst or takes part in the reaction, we have found these characteristics of the material to be highly advantageous. When a lead sodium alloy, produced by this method, is employed in the manufacture of alkyl lead compounds, the use of such material results in a 30 smoother, more efficient and complete reaction at higher speed than is possible with similar material obtained by other processes.

While we have disclosed the preferred embodiments of our invention, it will be readily apparent to those skilled in the art that many variations and modifications may be made therein without departing from the spirit of our invention. Accordingly, the scope of our invention is to be 40 limited solely by the appended claims, construed as broadly as is permissible in view of the prior art.

We claim:

1. The method of making comminuted solid material which material is of the character of 45 lead-sodium alloy, which comprises depositing a mass of molten material of said character upon a surface sufficiently cold to quickly solidify the molten material, instantaneously, upon cooling of said material, removing the solidified material 50 from the cooled surface, and simultaneously comminuting the removed material, so that such cooling, removing and comminuting are performed without appreciable lapse of time between them.

2. Lead-sodium alloy obtainable by the method of claim 1.

3. In a machine adapted to the solidifying and comminuting of molten metal in the character of molten lead-sodium alloy, without appreciable 60 lapse of time between solidifying and comminuting, in combination: a stationary, horizontal, cylindrical drum-like shell, having provisions for cooling the same and also having a smooth uninterrupted inner periphery, whereby the shell 65 is adapted to receive upon its inner surface the molten metal to be comminuted, as thrown thereon by the hereinafter recited rotor, and to cool and solidify the same in condition to be readily removed from such surface, a rotor concentrically received in said shell and of a diameter closely approaching that of the interior of the shell, said rotor being provided substantially throughout its length with a plurality of radially projecting spirally arranged edged tools of a length to ap- 75

- proximately bridge the space between the rotor and the shell, thus to bring the ends of the tools into close proximity to the shell, said shell being provided with a charging inlet and a discharge outlet, both of small area relative to the surface of the shell, wherefor the shell fully surrounds the rotor, said inlet and outlet being spaced apart along the length of the rotor and said inlet being located upon said shell in position to discharge directly upon a portion of the cylindrical surface of the rotor which is in casting relation to the shell immediately after passing the inlet during the rotation of the rotor.
4. A machine as claimed in claim 3 wherein the rotor has provisions for cooling the same.
5. In a device for making solid comminuted material, a stationary shell having an inner cylindrical surface, said shell comprising two semi-cylindrical halves having flanges and means for securing the same together, each semi-cylindrical half having a jacket covering but spaced from the outer surface thereof and rigidly secured thereto, a plurality of partitions in the space between the jacket and the outer surface of each semi-cylindrical half, short longitudinally spaced pairs of said partitions extending circumferentially from opposite longitudinal edges of each semi-cylindrical half and terminating short of the median of the circumference thereof alternated with single long partitions extending circumferentially across the median of the circumference of the semi-cylindrical half and terminating short of the longitudinal edges thereof and intermediate of the lengths of the short par-

titions, each of said jackets having inlets and outlets at opposite ends thereof whereby a fluid heat transfer medium may be circulated through the spaces between the jackets and the semi-cylindrical halves.

6. In a device for making solid comminuted material, a stationary jacketed shell having an inner cylindrical surface, a rotary member within the shell, said rotary member comprising a rotary shaft, a cylinder rigidly mounted on said shaft and having an outer cylindrical surface positioned adjacent to but spaced from the inner cylindrical surface of the shell, an inner cylindrical jacket positioned adjacent to but spaced from the inner surface of the cylinder, a spiral partition between the jacket and the cylinder extending circumferentially of the jacket and advancing from one end of the jacket to the other end, a fluid inlet extending through one end of the shaft and into one end of the space between the jacket and the cylinder, a fluid outlet extending through the other end of the shaft and into the other end of the jacket whereby a fluid heat transfer medium may be circulated through the space between the jacket and the cylinder, edged tools rigidly secured to and projecting from the outer cylindrical surface of the cylinder and having their edges positioned closely adjacent to the inner cylindrical surface of the shell, and means for rotating the rotary member.
